UNITED STATES PATENT OFFICE.

EUGENE F. OSBORNE, OF CHICAGO, ILLINOIS, ASSIGNOR TO OSBORNE STEAM ENGINEERING COMPANY, OF CHICAGO, ILLINOIS, A CORPORATION OF ILLINOIS.

STEAM-SEPARATOR.

SPECIFICATION forming part of Letters Patent No. 790,849, dated May 23, 1905.

Original application filed November 23, 1903, Serial No. 182,334. Divided and this application filed May 12, 1904. Serial No. 207,657.

To all whom it may concern:

Be it known that I, EUGENE F. OSBORNE, a citizen of the United States, residing at Chicago, in the county of Cook and State of Illinois, have invented certain new and useful Improvements in Steam-Separators; and I do hereby declare that the following is a full, clear, and exact description thereof, reference being had to the accompanying drawings, and

10 to the letters of reference marked thereon, which form a part of this specification.

This invention relates to improvements in steam-separators and grease-catchers for the purpose of separating from steam water carried in suspension therein and grease or other substances carried by the steam. Said device may be located either between the steam-generator and the engine or may be located in the exhaust-pipe of the steam-engine in cases

20 where the exhaust-steam is used for heating or like purposes. Such latter use of the invention is illustrated in my copending application for United States Letters Patent, Serial No. 182,334, filed November 23, 1903, and of

25 which this application is a division.

The invention consists in the matters hereinafter set forth, and more particularly pointed out in the appended claims.

In the drawings, Figure 1 is a vertical section of a steam-separator made in accordance with my invention. Fig. 2 is a transverse section of the upper end thereof. Figs. 3 and 4 are details illustrating the internal construction of the parts in the separating-chamber.

30 As shown in said drawings, the device consists generally of a separating-chamber A and a water and grease collecting chamber B. Said separating-chamber is provided on opposite sides with steam inlet and exit passages

40 a a'. The two parts of the device may, if desired, be made of a single casting, but as herein shown is made of two parts joined together by means providing steam-tight joints. Located within said separating-chamber A,

45 and in the path of the steam as it passes from the inlet to the outlet are a plurality of intercepting or baffle bars. (Indicated as a whole in Fig. 1 by the reference-letter A' and shown

in Figs. 3 and 4.) Said bars extend between and are affixed at their upper and lower ends 50 to horizontal plates A² A³, the lower one of which is supported on the upper end of the wall of the collecting-chamber, while the upper plate fits closely within the separating-chamber, but is not affixed thereto. The upper wall A¹⁰ of the separating-chamber is made removable, whereby said bars and plates may be removed. Said intercepting-bars are made of a non-corrosive metal—such, for instance, as copper—and the condense-water carried 60 by the steam and grease or other foreign substances are intercepted by and deposited upon said bars, while the steam passes between the bars. The intercepted or accumulated water and other foreign substances pass by gravity 65 down said bars and into the water and grease collecting chamber B. The lower plate A³, which constitutes the partition between the separating and collecting chamber, is provided with openings a², through which the water 70 and grease passes to the chamber B below. Said collecting-chamber B is provided at its lower end with a discharge-passage embracing a part b, which is controlled by a float b', the valve being formed on the end of a reciprocating part or piston b². The construction of 75 the valve and the outlet for the liquid contents of said chamber constitutes no part of the present invention and need not be further herein described. The movable part of the 80 valve is connected by a link b³ with a float-controlled lever B', said lever being pivoted at one end to a bracket b⁴ in the chamber and provided at its other end with a suitably-shaped float B². The collecting-chamber is provided 85 at its lower part with a normally closed drain-pipe B⁵ and is provided at one side with a gage B⁴. The float-controlled valve is opened at a certain level of the liquid with the chamber to open the valve and partially empty said 90 chamber. The said intercepting-bars A' are of trough or V shape in cross-section and are arranged with their open sides directed toward the steam-inlet of the separating-chamber. Said bars are located over openings a² 95 in the lower plate A³, whereby water collected

thereon falls through said plate into the collecting-chamber below. The said bars are fixed to the upper and lower plates A² A³ by means of blocks a⁶ a⁷, attached to said plates 5 in any suitable manner, the former extending across the open sides of the bars and engaging the margins thereof and the latter being shorter and engaging the side faces of the oblique sides of the bars. Said holding-blocks 10 thus hold the bars from lateral displacement while the plates A² A³ are in place, while providing for ready detachment and removal of the same from the separating-chamber. Contained within said trough-shaped bars A' are 15 bars a³, which extend substantially across the bars from one side to the other. Said bars a³ are constructed to permit water and grease to pass behind the same into the space bounded at the front by said bars a³ and at the rear by 20 the inclined meeting sides of the bars A' or the closed sides of said bars. As herein shown, access of water and grease to the rear of the bars a³ is afforded by notches a⁵ in the margins of said bars; but the same general 25 effect will be produced by stopping the margins of the bars a³ short of the inner faces of the inclined sides of the bars A'. Preferably said bars a³ are made of trough or V shape, with their salient angles directed toward the 30 steam-inlet side of the separating-chamber. Said bars a³ are engaged at their salient angles by the front holding-blocks a⁶ and are thus held in place.

The force of the steam acting against the 35 inner faces of the bars A and the outer faces of the bars a³ tends to drive the liquid (as the water and grease) which is deposited from the steam on said bars through the notches or openings a⁵ into the space between the angles 40 of the bars A' and the bars a³. Inasmuch as said space is not subjected to the direct kinetic energy of the steam to the same extent as are the more exposed faces of said bars, the liquid deposited out of the steam runs by gravity 45 down said bars more freely than on the surface of the bars so exposed to the direct action of the passing steam. The said deposited liquid is divided more thoroughly from the steam, and less opportunity is afforded for the 50 liquid so divided out from again being caught up and carried away from the steam than if all parts of the collecting-surfaces of the bars be equally exposed to the action of the steam.

It will be noted that the open sides of the 55 V-shaped bars A' are somewhat wider than the spaces between adjacent bars, thereby preventing the steam passing directly through the separating-chamber, but compelling it to assume a zigzag course in its passage there- 60 through.

I claim as my invention—

1. A steam-separator comprising a separating-chamber provided with steam inlet and outlet passages, a collecting-chamber beneath 65 the same and of substantially the same diam-

eter as the separating-chamber, intercepting-bars extending across said separating-chamber, a plate located between the separating and collecting chambers and supporting said intercepting-bars, and provided with openings at the lower ends of said bars, the upper wall of the separating-chamber being removable, a plate within the upper end of the separating-chamber beneath the upper wall thereof to which the upper ends of the bars are fixed 70 to prevent lateral displacement thereof, and a trapped outlet for said collecting-chamber. 75

2. A steam-separator comprising a separating-chamber provided with steam inlet and outlet passages, a collecting-chamber located 80 to receive the water of condensation by gravity from the separating-chamber, a plurality of trough-shape intercepting-bars extending across the separating-chamber between the inlet and outlet steam-passages, said intercepting-bars being arranged with their open sides directed toward the steam-inlet, and bars located within and extending across the trough-shape bars from side to side thereof and provided at their side margins, between 85 the same and the inner faces of the side members of the intercepting-bars, with notches or spaces.

3. A steam-separator comprising a separating-chamber provided with steam inlet and outlet passages, a collecting-chamber located to receive the water of condensation by gravity from the separating-chamber, a plurality of trough-shape intercepting-bars extending across the separating-chamber between the 90 inlet and outlet passages, said intercepting-bars being arranged with their open sides directed toward the steam-inlet side of the separating-chamber, a plate or partition between the separating and collecting chambers and provided with openings over which said bars are seated, and longitudinally-arranged bars located within and extending across said trough-shape intercepting-bars and from side to side thereof and provided at their margins 95 with notches or openings.

4. A steam-separator comprising a separating-chamber provided with a steam-inlet and a steam-outlet, a collecting-chamber, a plate or diaphragm separating said chambers, a float-controlled liquid-outlet for said collecting-chamber, a plurality of vertically-disposed intercepting-bars in the separating-chamber between the inlet and outlet thereof, and resting on said plate or diaphragm, said diaphragm being provided with openings at the lower ends of said bars, said bars being made of trough shape with the open sides thereof directed toward the steam-inlet side of the separating-chamber, and trough-shaped bars in 115 the open sides of said intercepting-bars and extending from side to side thereof, and arranged with their closed sides toward the steam-inlet side of the separating-chamber and with their side margins engaging the inclined 120 125 130

sides of the intercepting-bar in a manner to permit fluid to pass therebetween.

5. A steam-separator comprising a separating-chamber provided with steam inlet and outlet passages, a collecting-chamber beneath the same, a horizontal removable plate forming a partition between said separating and collecting chambers and provided with openings, a plurality of vertical intercepting-bars 10 in said separating-chamber standing over said openings in said partition, a second horizontal removable plate at the top of said separating-chamber and means for detachably af-

fixing said bars to said upper and lower plates, said separating-chamber being provided with 15 a removable top whereby said bars and upper and lower plates may be separately removed from said separating-chamber.

In testimony that I claim the foregoing as my invention I affix my signature, in presence 20 of two witnesses, this 9th day of May, A. D. 1904.

EUGENE F. OSBORNE.
